ELECTRIC DEVICE

William Gregor Moran, Bloomfield, N. J., assignor
to Westinghouse Lamp Company, a corporation
of Pennsylvania

Application April 29, 1933, Serial No. 668,527

7 Claims. (Cl. 250—27.5)

This invention relates to electron discharge devices and more particularly to devices of this character adapted to be employed in the electric field. In its more specific aspect the invention is directed to an improved electron discharge device having improved mechanical characteristics and adapted to operate uniformly over an extended period of time.

Electron discharge devices, and especially those employed in the radio field generally comprise a plurality of electrode elements located in a vitreous envelope. Some of these elements are of somewhat delicate mechanical design and sometimes because of the peculiar mounting of the same in said envelope they may become distorted or displaced from their original positions so that the function of the tube is seriously impaired or they may be broken so as to render the tube useless.

My invention is directed to the obviation of these difficulties by providing a means that serves to maintain the electrodes in their original spaced relationship and to decrease the liability of distortion or breakage of the more fragile elements during transportation or when subjected to normal operating conditions.

Another object of my invention is to provide an electron discharge device having rugged mechanical characteristics and adapted to have uniform electrical characteristics when operated over an extended period of time.

Another object of my invention is to provide an electron discharge device of such mechanical construction that the same may be transported and operated without distortion, displacement or breakage of the delicate elements therein contained.

Another object of my invention is to provide an electron discharge device of rigid construction and which may be economically manufactured.

The above and other objects of my invention will become readily apparent from the following specification and drawing wherein,

Figure 1 represents a longitudinal cross sectional view with some of the parts in elevation of an electron discharge device embodying my invention.

Figure 2 represents a fragmentary perspective view of an electron discharge device embodying my invention.

Figure 3 is a perspective view of a fragment of the structure shown in Figures 1 and 2 and illustrates a modified constructional detail as part of my invention.

Figure 4 represents a view similar to Figure 3

and illustrates a further modified constructional detail as part of my invention.

As shown in the drawing the electron discharge device includes an evacuated vitreous envelope 10 having a reentrant stem 11 of appreciable length. The upper or free end of the reentrant stem 11 is in the form of a pinch or press 12 in which are hermetically sealed a plurality of spaced leading-in and supporting conductors 13, 14 and 15. These supporting conductors, 10 sealed in the press, extend interiorly and exteriorly of said envelope.

Welded to and electrically supported by said leading in and supporting conductor 15 is a supporting rod 16 which is in electrical contact with 15 said rod 15 and extends parallel to the central longitudinal axis of said envelope. Welded to the supporting rods 13 and 14 and extending upwardly in said envelope are respective cathode supporting rods 17 and 18. 20

A cruciform insulator 19 consisting of cross arms 20 and 21 arranged at right angles to each other and composed of an insulating material, such as lavite or the like, is located above said press and has vertical openings therein to accommodate the supports 16, 17 and 18 which extend therethrough. An inverted W-shaped filament 22 that is to serve as the electron emitting element or cathode has its free ends welded to the free ends of the respective supports 17 and 18. 30 The lower bight of said filament 22 is located in and bears against a hook 23 having a shank extending through a vertical opening in the center of said insulator and fixedly secured thereto.

A rod 24 substantially parallel to the rod 16 35 also extends through an opening in the arm 21 of said insulator 19. These two rods 16 and 24 respectively located at the openings near the extremities of the cross arm 21, serve to support a grid wire 25 which comprises a helix of fine 40 wire wound therearound and suitably secured thereto. Short metallic cross bars 26 and 27 are welded respectively to those portions of the rods 16 and 24 just below the insulator 19. These cross bars serve to prevent grid displacement in 45 a vertical direction. In place of the cross bars I may mash the rods 16 and 24 at the portions thereof just below the insulators to provide enlarged sections serving the same purpose as said bars.

According to my invention a resilient metallic band or sleeve 28 is clamped around the reentrant tube 11 slightly below the press and is in frictional engagement therewith by virtue of the nut and bolt arrangement 29. 50 55

That portion of the reentrant tube 11 around which the band 28 is wrapped is preferably roughened by means of sand blast or hydrofluoric acid for friction purposes. Welded to the 5 outer portion of said band 28 are a plurality of spaced rigid supporting standards 30 and 31. The distance between said supporting standards at the junctions between the same and the sleeve 28 corresponds to about a 60° arc.

10 These supporting standards 30 and 31 extend upwardly and are bent towards each other along their length and are welded together at the position where the shorter one 30 terminates. The supporting standard 30 is of such a length as 15 to extend a small distance above the supporting rods 13, 14 and 15. The supporting standard 31 is of such a length as to extend materially above said supporting rods 13, 14 and 15 as shown to extend up to the upper extremity of the supporting rod 16.

From that point where the supporting standard 30 is welded to the supporting standard 31 the supporting standard 31 extends substantially parallel to the longitudinal axis of the envelope 25 and to the supporting rods 16 and 24.

On the other side of said press and in a diametrically opposed relationship to said respective supporting standards 30 and 31 are a pair of similar standards 32 and 33. The supporting standards 32 and 33 are respectively of the same configuration and of substantially the same length as the supporting standards 30 and 31, with the upper end of the supporting standard 33 being in substantially the same horizontal plane as the 35 upper end of the supporting standard 30. In the same manner as supporting standards 30 and 31, the supporting standards 32 and 33 are spaced from each other at one end, welded to the band 28 and welded to each other at the end of standards 40 and 33.

The supporting standards 31 and 33 extend through respective vertical perforations located near the extremities of the cross arm 20 of the insulator 19. This insulator has the outer ends 45 of its cross arm 20 in contact with and resting upon the upper end of the supporting standards 30 and 32 which may be slightly flattened or flanged thereat. The supporting standards 30, 31, 32 and 33 serve as a seating means for the 50 insulator 19 to maintain the same spaced from said press. The insulator 19 aligns the elements that pass therethrough.

Relatively short discs 34 of carbon or the like, have central openings therein to accommodate 55 the respective supporting standards 31 and 33, with each disc being of substantially the same height. These discs rest upon the outer ends of the cross arm 20 and have the supporting standards 31 and 33 extending therethrough. Also 60 mounted upon said supporting standards 31 and 33, and as shown, supported by the upper parallel portions thereof, is a unitary composite rigid anode 35 composed of carbon or the like, and of the type disclosed in the application Serial No. 65 673,865 of George M. Dinnick filed June 1, 1933, and entitled an Electron discharge device and anode therefor.

The anode comprises an elongated hollow member consisting of two flat sides arranged parallel 70 to each other and integral with two curved portions forming the other sides. A cross sectional view of said anode at right angles to its major axis is in the form of a rectangle having rounded ends. At the mid width of said flat sides and 75 extending along the entire length thereof are

lateral extensions. Each extension of appreciable cross sectional area has an opening therethrough and along the length thereof parallel to the longitudinal axis thereof.

The diameter of these openings is about the 5 same as that of the supporting standards 31 and 33 so that the anode can be slid down on these two supporting standards. These two supporting standards 31 and 33 extend through the vertical openings in the anode which rests upon the discs 34. Also mounted on said supporting standards 31 and 33 are a pair of discs 36 of the same type and configuration as the discs 34, and like the discs 34 serve to space the lavite insulator away from the anode, which becomes 15 highly heated during tube manufacture. These discs rest upon the lateral extensions of the anode. Resting upon the discs 36 is a cruciform upper insulator 37 having cross arms 38 and 39 and composed of an insulating material, such as la- 20 vite or the like.

The supporting standards 31 and 33 extend through openings in the cross arm 38, these openings being in line with the openings in the arm 20, so that the anode is aligned in proper 25 spaced relationship with respect to the other electrodes. These supporting standards 31 and 33 being in contact with the anode act as a lead therefor. A suitable potential may be applied to the anode through these supporting standards 31 and 33 electrically connected to an electrical conducting lead 40 welded to the rod 33. The lead 40 is hermetically sealed in the reentrant stem an appreciable distance below the press 12 and extends exteriorly and interiorly of 35 said envelope.

The other cross bar 39 of said insulator 37 has a plurality of spaced vertically disposed openings therein with the openings at the outer ends thereof being adapted to accommodate the rods 16 40 and 24 which project upwardly therethrough.

Weldedly secured to the rods 16 and 24 at the portions thereof immediately adjacent the upper face of said insulator 37 are cross bars 38. Projecting through the two spaced intermediate 45 openings are the shanks of resilient hook members 41 having the spring portions thereof resting upon the insulator, with the hook portions thereof surrounding and in contact with the two upper bights of the filament 22. These spring 50 members cooperating with the lower hook and the supports 17 and 18 retain the filament in a taut and upright position, properly spaced from the other electrodes.

In further accordance with my invention I 55 provide tie rods 42 and 43 to prevent cathode breaking or distortion or derangement of any other electrode and to maintain the electrodes in their original positions during normal transportation or operation.

This result may be accomplished by employing the two inverted U shaped rods 42 and 43 in the manner illustrated. The rod 42 having a cross piece 44 and legs 45 and 46 is so positioned that the cross piece 44 rests upon the upper face of the 65 cross arm 38 and immediately adjacent that portion of the supporting standard 31 extending above said cross arm 38. With the rod 42 in this position a tensile force is applied to the legs 45 and 46 to maintain the elements 19, 34, 35, 36 70 and 37 in firm contact with each other. While the tensile force is still applied to the legs 45 and 46 now under suitable tension, the ends of legs 45 and 46 are welded to the lower portions of the supporting standards 30 and 31 at the 75

places where the supporting standards 30, 31 and the legs 45 and 46 meet. Then the cross piece of the U rod is welded to that portion of the standard immediately adjacent and above the 5 insulator 37.

The rod 43 having a cross piece and legs similar to the rod 42 is mounted in a similar manner and diametrically opposite the rod 42, with the rod 43 while under tension and secured by welding to the upper end of the supporting standard 33 and to the lower portion of the supporting standards 32 and 33 at the places of meeting of the supporting standards 32 and 33 and the legs of rod 43.

15 The legs of the rods 42 and 43 are substantially parallel as shown and are assembled always under suitable tension to maintain the elements 19, 34, 35, 36 and 37 in firm contact with each other. These rods 42 and 43 together with the supporting 20 standards provide a rigid structure which decreases the liability of electrode distortion or displacement because bending in any direction is substantially precluded.

As shown in Figures 1 and 2 the cross pieces 25 of the rods 42 and 43 are located adjacent and between vertical standards and the ends of the cross arm 38. It is within the purview of my invention to have the cross pieces of the rods 42 and 43 located on the other side of the vertical standards and secured thereto as shown in Figure 3. The construction disclosed in Figure 3 further differs from that of Figures 1 and 2 in that the cross piece of the rods 42 and 43 are 30 slightly curved to provide a seat for the upper ends of the standards.

A further modification of the cross piece is 35 shown in Figure 4 where the cross piece of the rods 42 and 43 may be pressed outwardly and having a perforated flattened portion through which the supporting standards 31 and 33 may project.

Instead of employing single piece inverted U-shaped rods 42 and 43, they may be formed of a 40 pair of longitudinally extending parallel and spaced rods welded to a separate metallic cross rod resting on the ends of the upper insulator as does the cross piece of the rods 42 and 43. The lower ends of these rods or those of the elements 42 and 43 may be welded directly to the band 28 45 instead of to the supporting standards 30, 31, 32 and 33 as illustrated.

For the purposes of providing a getter material in the envelope I may mount a getter 49 on the leg 45 in the manner shown.

50 Because my invention is susceptible to modifications, it is to be limited only by the prior art and not by the particular construction herein specifically described.

What is claimed:

60 1. An electric device including a stem, a plurality of electrode supports carried by said stem, a lower insulator spaced from said stem, and an upper insulator spaced from said first insulator, a plurality of electrodes in electrical contact with 65 said supports, one of said electrodes being rigid and surrounding the other electrodes, said supports including a plurality of standards extending through openings in said insulators, means carried by said stem for limiting downward movement of said lower insulator and a plurality of inverted U shaped members each member having its cross arm secured to the upper part of one 70 of said standards and the longitudinal arms thereof secured respectively to the lower part of each of said standards and to said first mentioned means.

2. An electric device including a stem, a cathode, a grid and a rigid anode, a lower cruciform insulator spaced from said stem, and an upper cruciform insulator also spaced from said stem, a band carried by said stem, two pairs of spaced 5 converging standards secured to said band, one of each pair of said standards extending through an opening of each of the cross arms of said insulators, said last mentioned standards extending through openings in said anode located between 10 said insulators, a plurality of supports extending through the other cross arm of said insulators and supporting the cathode and grid, said other standards carried by said band limiting the downward movement of said lower insulator and a U-shaped rod mounted near one end of said insulator adjacent said standards and secured to said rods.

3. An electric device including a stem, a plurality of conductors sealed in said stem, a lower 20 insulator spaced from said stem, an upper insulator spaced from said lower insulator, said insulators having the configuration of a cross and having openings therein, a cathode, a grid and an anode located between said insulators, 25 supporting elements extending through the openings in one of the cross arms of said lower insulator and through openings in the cross arms of the upper insulator and connected to said cathode and grid, a plurality of standards carried by said stem, said standards extending through openings in the other cross arms of said insulators, a plurality of additional supporting standards carried by said stem for positioning said lower insulator, inverted U shaped rods secured to said standards at two places and also secured to said additional supporting standards. 30

4. An electric device comprising a stem, upper and lower insulators spaced from said stem and from each other, said insulators being cruciform 40 and having openings therein, a cathode and a grid located between said insulators, supporting means for said cathode and grid, some of said supporting means extending through one of the cross arms of the lower insulator and some of 45 said supporting means extending through the cross arm of the upper insulator, a plurality of standards carried by said stem, said standards extending through openings in the other cross arms of the upper and lower insulators, inverted 50 U shaped rods having their cross arms located over the upper insulator, the cross arms of said U shaped rods being secured to said standards, additional supporting standards also carried by said stem and in abutting relation with the lower 55 insulator, the long arms of said U shaped rods being secured to said standards and said additional supporting standards.

5. An electric device comprising a stem, an upper insulator and a lower insulator spaced from 60 said stem and from each other, a plurality of conductors sealed in said stem, an anode, a cathode and a grid located between said insulators, said insulators being cruciform and having openings therein, conductors extending through one of the cross arms of the lower insulator and connected to said cathode and grid and also to said conductors, means extending through openings in one of the arms of the upper insulator for supporting said cathode, said upper insulator being 65 supported by said anode, a plurality of standards extending through the other cross arms of said insulators, U shaped rods having the cross arms thereof secured to said standards at positions 70 over the upper insulator, additional supporting 75

standards also carried by said stem for limiting downward movement of said lower insulator, the long arms of said inverted U shaped rods being secured to said standards and said additional 5 supporting standards.

6. An electric device including a stem, a rigid anode spaced from said stem, an insulator, a pair of standards carried by said stem and extending through openings in said insulator, a second insulator spaced from said first insulator and having openings through which said standards project, upwardly extending additional supporting standards carried by said stem and secured to said standards for limiting downward movement 10 of said first mentioned insulator, said anode being supported by said first mentioned insulator and said standards, and means for preventing lateral displacement of said anode, said means

including two pairs of spaced rods cooperating with said upper insulator and secured to said standards.

7. An electric device including a stem, a rigid anode spaced from said stem, a plurality of spaced insulators having openings therein, a band encircling said stem, a plurality of supporting standards secured to said band and spaced from each other, two of said supporting standards limiting the downward movement of one of said insulators, the other two of said supporting standards extending through openings in both of said insulators, a pair of inverted U-shaped elements having the short cross arms thereof extending over the upper face of the upper insulator and having the longitudinal arms thereof secured to said rods carried by said band. 10 15

WILLIAM GREGOR MORAN.
